ICE TRAY

Gunnar Grubb, Stockholm, Sweden, assignor, by
mesne assignments, to Servel, Inc., New York,
N. Y., a corporation of Delaware

Application February 23, 1937, Serial No. 126,969
In Germany March 6, 1936

8 Claims. (Cl. 62—108.5)

My invention relates to ice trays for use in household refrigerators, and has for its object to provide an improved ice tray from which ice is readily removed without the necessity of using heat or water. More particularly, it is an object of my invention to provide an improved ice tray and a device co-operating therewith to facilitate the removal of its frozen contents. I accomplish these objects by providing a tray body having a side wall which is normally bowed inwardly for a substantial distance in a lengthwise direction. The bond between the bowed side wall and ice is readily broken by expanding the side wall with outward movement thereof from an opposite side wall. The extent of outward movement of the bowed side wall to break the ice bond is relatively small, and, after peeling and shearing has once been started at the upper surface of the ice, such peeling and shearing progresses readily about the side walls and along the tray bottom due to the fact that the inward bulge of the bowed side wall extends for a substantial distance in the direction of its length.

In order to facilitate the removal of ice from a tray body of the character just described, I also provide a device which is operative to expand the inwardly bowed side wall and cause outward movement thereof. The device may be so constructed that, after the bond between the ice and bowed side wall has been broken, the device is operative to separate the ice from the tray body.

The invention, together with the objects and advantages thereof, will become apparent from the following description taken in conjunction with the accompanying drawing forming a part of this specification, and of which Fig. 1 is a plan view of an ice tray embodying my invention; Fig. 2 is a front view of the ice tray shown in Fig. 1; Fig. 3 is a fragmentary sectional view taken on line 3—3 of Fig. 1; Fig. 4 is a fragmentary plan view of a modification of the ice tray shown in Fig. 1; and Fig. 5 is a fragmentary sectional view taken on line 5—5 of Fig. 4.

In Fig. 1, I have shown an ice tray 10 having resilient bottom and side walls. The tray is preferably made of suitable metal, such as aluminum or stainless steel, for example, and about the upper edges of the side walls is provided an outward extending flange 11. The tray 10 is so formed that one side wall 12 is normally bowed inwardly for a substantial distance in a lengthwise direction. The bowed portion of side wall 12 is slightly less than the distance between the adjacent opposing side walls and presents a single curved surface having a relatively large radius of curvature.

When ice is produced in the tray 10 and it is desired to remove the ice from the tray, the bond between the ice and the inwardly bowed side wall

12 is readily broken by outward movement of the side wall. Due to the inward bulge of the side wall 12, it is stretchable and capable of being expanded, whereby peeling and shearing at the upper surface of the ice can readily be initiated to loosen and break the bond between the ice and the side wall.

In order to facilitate the breaking of an ice bond in a tray of the character just described, I provide a force multiplying device for causing outward movement of the inwardly bowed side wall. To this end the flange 11 at the upper edge of the bowed side wall 12 is broken away intermediate its ends, and at each end of the side wall the flange is looped to form sleeves 13 adapted to receive a pin 14. The pin 14 is provided with levers 15 at each end which are connected by a cross member 16 which serves as a handle to operate a cam or eccentric 17 fixed to the pin 14. A strong leaf spring 18 is disposed at the same level as the eccentric 17 and its ends are secured in any suitable manner, as by riveting or welding, for example, to the outer surface of the bowed side wall 12. The leaf spring 18 extends across the side wall 12 and is substantially parallel to the bottom of the tray body 10. The spring 18 is secured to the side wall 12 in such a manner that it is normally under tension and is bowed outwardly, as shown most clearly in Fig. 1.

In using the tray 10 and device just described, the tray is filled with water and placed in a cooling unit of a refrigerator. After the water has been frozen, the tray is taken out of the cooling unit with the levers 15 and eccentric 17 in the position shown in Figs. 2 and 3. The levers 15 are then pulled upwardly by the handle 16 toward a horizontal position. With such upward movement of the levers 15 the eccentric 17 turns and exerts a force on the flat spring 18 and tends to straighten out the latter. Due to the straightening out action of the spring 18 the inwardly bowed side wall 12 also tends to expand and straighten out, and, with the application of forces in opposite directions on the side wall 12 at the ends of the spring 18, the side wall 12 is caused to move outward to break the bond between the ice and the side wall. In other words, an inward movement of the outwardly bowed leaf spring 18 causes an outward movement of the inwardly bowed side wall 12 with the connecting points of the spring and the side wall tending to move away from each other.

Although the extent of outward movement of the bowed side wall 12 may not be very great, it is nevertheless sufficient to break the bond between the ice and the side wall. The arrangement of the levers 15, eccentric 17, and the leaf spring 18 is such that the force applied to the levers 15 is multiplied many times, whereby ex-

panding of the bowed side wall 12 is readily effected by inward movement of the outwardly bowed leaf spring 18.

In Figs. 4 and 5 I have shown a modification of the invention wherein the device, in addition to breaking the bond between the ice and the bowed side wall 12 of the tray, is also operative to exert a separating force between a grid structure 19 and the tray body 10. The grid structure 19 may consist of two zigzag-shaped partitions 20 and a centrally disposed straight partition 21 connected at their ends by a cross member 22. The cross member 22 is provided with a flange 23 which is adapted to extend over the upper edge 10] of the side wall 12 adjacent the eccentric 17. In 15] operation, the levers 15 are pulled upward by the handle 16 in the same manner as in the embodiment just described to break the bond between the side wall 12 and the ice. With continued 20] upward movement of the levers 15 after the ice bond at the front end wall 12 has been broken, the eccentric 17 becomes operative to exert an upward force on the flange 23 to cause the grid structure 19 to separate from the bottom of the tray with the ice clinging thereto. After the ice bond is once broken at the front end wall 12, the continued upward movement of the levers 15 causes a gradual peeling and shearing of the ice from the side walls and along the bottom of the tray, whereby the removal of the grid structure 19 and ice is readily effected. The eccentric or cam 17 in this instance is preferably so shaped that when it is first turned force is primarily transmitted to the leaf spring 18 to cause outward movement of the bowed side wall 12. When the ice bond is once broken and the eccentric 17 is turned further, the shape of the eccentric is such that force is primarily transmitted to the grid structure to cause separation of the latter 40] from the tray body 10.

Although I have shown and described particular embodiments of my invention, it will be apparent that modifications and changes may be made without departing from the spirit and 45] scope of my invention, as defined in the following claims.

I claim:

1. An ice tray having resilient metallic side walls and a bottom wall, one of said side walls 50] being normally slightly bowed inward, said tray being constructed and arranged so that outward movement of said flexible bowed side wall will spread apart the side walls connected to the ends of said bowed side wall to break an ice bond between said tray walls and ice contained therein, and means to cause outward movement of said bowed side wall by force applied in a region intermediate the ends of said bowed side wall and in a direction opposite to said outward movement.
- 55] 2. In combination with an ice tray for refrigerators adapted to hold water to be frozen and having a resilient bottom and side walls, one of said side walls being so shaped and formed that it is expandable, a resilient member having the ends thereof secured to the outer surface of said one side wall at spaced points, and said resilient member being so constructed and arranged that, when force is applied to an intermediate region thereof, its ends are spread apart to cause elongation of said expandable wall in the direction of its length and thereby break the ice bond between the expandable wall and ice contained in said tray.
- 70] 3. In combination with an ice tray for re-

frigerators adapted to hold water to be frozen and having a resilient bottom and side walls, one of said side walls being normally curved and slightly bowed inwardly, a flexible member extending in the direction of said bowed side wall 5 and having its ends arranged to cooperate with said tray at spaced points, and said flexible member being so constructed and arranged that, when force is applied to an intermediate region thereof, its ends are spread apart to cause outward movement of said bowed side wall and thereby break the ice bond between said bowed side wall and ice contained in said tray.

4. Apparatus for producing ice pieces including a tray member adapted to hold water to be frozen 15 and having a substantially flat resilient bottom and substantially straight side walls, a grid removably fitting in said tray, one of said side walls normally being curved and slightly bowed inwardly, mechanism operative to cause outward 20 movement of said bowed side wall to break an ice bond between said bowed side wall and ice contained in said tray, and, while said bowed side wall is being urged outward, said mechanism also being operative to lift said grid bodily away 25 from the bottom of said tray.

5. Apparatus for producing ice pieces including a tray member adapted to hold water to be frozen and having a substantially flat resilient bottom and substantially straight side walls, a grid member 30 removably fitting in said tray member, one of said side walls normally being curved and slightly bowed inwardly, said tray being so constructed and arranged that outward movement of said bowed side wall by force applied thereto 35 will cause spreading apart of the side walls connected to the ends of said bowed side wall, mechanism operative to cause such outward movement of said bowed side wall, and said mechanism also being operative to lift said grid member bodily 40 away from the bottom of said tray member when it is being operated to cause outward movement of said bowed side wall.

6. An ice tray having a deformable side wall, a flexible member disposed lengthwise of said side 45 wall and having the ends thereof secured to the outer surface of said side wall, and mechanism including a part movable toward said deformable side wall and operable to exert force on said flexible member to cause the outer ends thereof to move away from each other to cause deformation of said side wall.

7. An ice tray having a deformable side wall, a flexible member disposed lengthwise of said wall and having the ends thereof secured to the outer surface of said side wall, and mechanism including a cam member rotatably mounted on said tray adjacent to said flexible member, said cam member being turnable to straighten said flexible member and cause deformation of said 60 side wall.

8. An ice tray having a deformable side wall, a flexible member disposed lengthwise of said side wall and having the ends thereof secured to the outer surface of said side wall, and mechanism 65 including a part movable toward said deformable side wall and operable to exert force on said flexible member to cause the outer ends thereof to move away from each other to effect deformation of said side wall, said mechanism 70 also being operative to exert a separating force between said grid member and said tray.

GUNNAR GRUBB.
